UNITED STATES PATENT OFFICE

WILLIAM LEONARD PADEN, OF DAYTON, OHIO, ASSIGNOR TO OHMER FARE REGISTER COMPANY, OF DAYTON, OHIO

CHECK EJECTING MECHANISM

Application filed May 29, 1930. Serial No. 457,272.

In machines which issue checks or receipts, the check issuing mechanism has not always proved satisfactory. In most such machines, if the check is not removed before 5 a second check is issued, serious consequences may result, by reason of the fact that the first check may prevent the successful issuance of the second check. In such instances, it is frequently found that the check 10 ejecting mechanism becomes clogged which may render the entire machine inoperative. The object of this invention is to provide means whereby the check is ejected with considerable force and yet is retained by a check 15 holding mechanism in such a position that succeeding checks will not be stopped. Another object of the invention is to provide means whereby a large number of checks may be issued without removing same from the 20 machine, and so that the checks which have been issued will not interfere with the checks being issued.

Figure 1 is a side elevational view of a 25 register of the type shown in the application of Albert S. Wheelbarger and Grover C. Coil, S. N. 65,532, filed October 29, 1925, having my invention incorporated therein.

Figure 2 is a perspective view of the check 30 ejecting mechanism.

Figure 3 is a side elevational view of the check issuing, ejecting and holding mechanism.

Figure 4 is a perspective view partly in 35 cross section showing the feed rollers, the knife, the check ejecting mechanism, and the check holding mechanism.

In the drawings I have shown a crank 40 handle 1 which is secured to a gear 2 mounted on a stud 3. The gear 2 meshes with, and drives a gear 4 connected to a Geneva gear 5, which intermittently drives a Geneva pinion 6 which meshes with and drives a pinion 8. The pinion 6 is secured to a stud 7. The pinion 8 is rigidly secured to a shaft 9.

Mounted on shaft 9 is an electro-plate 10. A feed roller 11 is mounted on a shaft 12 and is normally in contact with the electro-plate 10. The gear 4 is provided with a wrist pin 13 which is connected to a wrist pin 14 by means of a pitman 15. The wrist pin

14 is anchored to an oscillating printing carrier 16, pivoted on a shaft 17. The printing carrier 16 is provided with a shaft 18, on which is rotatably mounted platen 20.

The base 19 of the machine is provided 55 with upstanding lugs 21 on which are pivoted brackets 22 which carry shaft 23 on which is mounted a supply paper roll 24. The strip of paper 25 from the said roll, passes upwardly over the platen 20 and between the 60 electro-plate 10 and feed roll 11, from whence it passes through an opening 26 in the fixed knife 27, which opening is just above the movable knife 28. The movable knife 28 may be operated by any suitable 65 means not shown, so as to sever the paper strip after it has passed through the said opening.

The gears 4 and 5 are mounted on a shaft 29 to which is anchored at its other end a 70 disk 30 provided with a V shaped cutaway portion 31. The side frame 32 is provided with a stud 33 having a head 34 serving as a guide for the lower end of a bar 35. The said bar 35 is bifurcated at its lower end to receive the said stud 33 and to be guided thereby. The bar 35 is bifurcated at its upper end, which bifurcation receives a stud 36 having a head 37, which stud is mounted 75 on a plate 38 secured to the side frame 32. The plate 38 carries a pin 39 and the bar 35 carries a pin 40 which pins are connected by a helical spring 41. The upper end of the bar 35 is provided with a bifurcated arm 42 which receives a crank pin 43 mounted on a lever 44, loosely mounted on a bar 45 carried by the side walls of the machine. The lever 44 extends beyond the bar 45 and is connected to a plate 46 which at its far end is anchored to a plate 47 having its journal 80 on a bar 45. The plate 46 is provided with two depending arms 48 which normally extend downwardly and slightly forwardly, and are then bent at 49 so as to extend almost straight downward and are again bent 85 at 50 so as to form extensions 51 which project downwardly and forwardly. These arms 48 are kicker arms to project the receipt forwardly after it has been severed. 90 As the ticket passes through the knife, it 95 100

strikes the lower edge of a plate 52 secured to a door 53 hinged to the base plate by means of a hinge 54. The lower edge of the plate 52 extends slightly downwardly from the 5 rear to the front, and approximately at the point where it contacts with the door 53 it is provided with a downwardly extending offset portion 55 adapted to deflect the forward end of the receipt downward. The 10 door 53 is provided with an opening 56 and below the opening a plate 57 is secured to the inner side of the said door. Plate 58 is secured to a flange 59 carried on the outer portion of the door 53 just above the opening 56. A plate 60 is hinged at 61 to the outer face of the door just below the opening 56.

In operation, the ticket strip 25 is fed forwardly by means of the said roller 11 and electro-plate 10, and after its feeding movement is complete, the knife severs same from the remainder of the strip. While it was fed forwardly and before being severed, the front end of the ticket strip was guided by 25 the lower edge of the plate 52, and engaged the offset 55 which bent the forward edge of the paper downwardly. As shown in Figure 3, when the knife severs the receipt or check, its rear end moves upwardly as 30 shown in dotted lines in Figure 3, so that its rear end is engaged by the extensions 51 of the kicker arms 48. At the end of the operation of the machine, the shaft 29 has completed its rotation and the V shaped cut- 35 away portion 31 is immediately above the pin 62 carried by an arm 63 anchored to the bar 35. The spring 41 now moves the bar 35 upwardly so that the pin 62 projects into the V shaped cutaway portion 31 of the disk 40 30 and this upward movement of the bar 35 snaps the outer end of the lever 44 upwardly, thereby propelling the kicker arms 48 forwardly so as to eject the receipt or ticket with considerable force into the receptacle 64, which receptacle is formed between the plates 58 and 60. The receipt drops, by gravity, so as to lie on top of the plate 60 so that it will be out of the way of a succeeding receipt or ticket.

50 I recognize the fact that receptacles for tickets are old but I believe that I am the first to have invented a machine that has a snap action for the ejection of the tickets or receipts. I realize that many changes may 55 be made in the specific form of the invention, which is disclosed by way of illustration in the annexed drawings and described in this application, without departing from the spirit of the invention, and I desire to claim 60 the same broadly, except as I may limit myself in the annexed claims.

I claim:

1. In a check ejecting mechanism, means to bend the forward end of the check downwardly so as to elevate the rear end thereof,

and means to engage the elevated end of the check and project the check forwardly.

2. In a check ejecting mechanism, a guide plate adapted to guide a check forwardly and downwardly so as to elevate the rear end thereof, and means to engage the elevated rear end and kick the check forwardly. 70

3. In a check ejecting mechanism, a guide plate provided with a downwardly extending offset portion adapted to guide a check forwardly and downwardly so as to elevate the rear end thereof, and means to engage the elevated rear end and kick the check forwardly. 75

4. In a check ejecting mechanism, an arm, a receptacle, hinged plates forming one wall of the receptacle, and means to cause said arm to engage a check and snap the check forwardly into the receptacle. 80

5. In a check ejecting mechanism, a rotatable disk provided with a slot, a bar, a pin carried by said bar, said slot being so positioned on said disk as to be adjacent said pin when the disk completes its rotation, means whereby the said pin is held on the periphery of said disk while the machine is being operated and is projected into said slot when the slot is brought adjacent to said pin, and means actuated by said bar to kick out a check when the said pin passes into the said slot. 85 90

In testimony whereof I affix my signature.

WILLIAM LEONARD PADEN.
